UNITED STATES PATENT OFFICE

JOHN C. CHAPPLE, OF ST. LOUIS, MISSOURI

LOCOMOTIVE ARCH

Application filed November 5, 1928. Serial No. 317,203.

This invention relates to improvements in locomotive arches, and more particularly to a simple and novel form or construction of the arch brick or unit.

It is the primary object and purpose of my present invention to provide an arch brick or unit of such construction that the same may be readily mounted and arranged between spaced supporting elements of the firebox structure, and will offer maximum and uniform resistance throughout that portion of the brick which is subjected to the greatest deteriorating effects of the intense heat of the combustion chamber and the abrasive action of particles of coal and ash.

It is common practice to provide inclined water tubes in a locomotive firebox extending from the lower portion of the flue sheet of the combustion chamber rearwardly and upwardly to the rear firebox sheet for the purpose of circulating the water and expediting and increasing steam production. In some instances it is also the practice to provide other water evaporating surfaces such as siphons for this purpose. It has likewise been common practice to arrange and support refractory bricks or units on the inclined water tubes, the siphons and side sheets of the firebox either directly, or indirectly by the provision of suitable supporting lugs or trunnions fixed to the siphons or side sheets to thereby provide a baffle between the upper portion of the combustion chamber and the lower portion of the firebox where combustion is initiated and the flue sheet. These refractory bricks or units have been made in various shapes, the present most favored forms being either flat with all parts of the brick positioned in a common plane, or one

40 having a concavo-convex form with curved upper and lower surfaces and variously shaped ends to seat upon the tubes or other supports. Brick of the latter type, as now made have their greatest thickness at the center line of the brick and gradually decrease in thickness from the brick center to opposite edges thereof. In the practical use of such brick, it has been found that the deteriorating effect of the intense combustion chamber temperature and the abrasive ac-

tion of coal and ash particles on the brick is just as severe at certain other portions as it is at the center of the brick so that such brick rapidly wear away and it is necessary to replace the same by new brick with more or less frequency.

It is the important feature of my invention to provide an arch brick construction whereby this condition is remedied, the useful life of the brick materially increased, and replacement thereof by new brick necessitated only after a comparatively prolonged period of useful service. To this end, in a preferred embodiment of the invention, the baffle brick is of general arch shape form, the upper and lower surfaces thereof being concentrically curved from radii on the center line of the brick and such surfaces extending over the major portion of one dimension of the brick on opposite sides of said center line so that such portion of the brick will have a uniform predetermined thickness. The upper surface of the brick at its opposite edges extends from shorter radii at each side of the center line of the brick and at a tangent to the intermediate upper curved surface of the brick. Thus, these opposite edge portions of the brick which rest or seat upon the spaced supporting elements of the firebox structure contain less refractory material or are relatively thin, since at these edge portions of the brick the effects of excessive temperatures and of abrasive action are less severe. This construction likewise permits heating of the brick to a more nearly uniform degree in all parts thereof, thereby obviating physical strains due to uneven expansion and contraction in the structure of the brick.

In accordance with my invention, the opposite edge portions of the brick which are adapted to be seated upon the supporting elements of the firebox structure may be formed or shaped in various different ways to meet varying conditions of use.

Having above briefly described the principal objects and purposes of my invention, reference may now be had to the accompanying drawings, wherein I have illustrated several desirable practical embodiments, and to the following description wherein these il-

lustrated constructions are described in detail.

Referring to the drawings, in which similar reference characters designate corresponding parts throughout the several views,

Figure 1 is a horizontal sectional view through a firebox equipped with a refractory arch embodying one form of my novel arch 10 brick;

Fig. 2 is a partial transverse section taken on the line 2—2 of Fig. 1, showing several of the intermediate or center brick of the arch and the side or wing brick supported in 15 an inclined position against the side sheet;

Fig. 3 is a similar sectional view showing the side brick supported in a horizontal position with its outer end resting upon a lug or trunnion fixed to the side sheet;

20 Fig. 4 is an enlarged top plan view showing one of the center brick arranged between spaced water tubes;

Fig. 5 is an enlarged edge view of one of the center brick diagrammatically indicating 25 the different radii for the differently curved upper surface sections of the brick;

Fig. 6 is an enlarged fragmentary view illustrating the construction of the outer edge of one of the side brick when mounted or 30 supported upon a lug or trunnion fixed to the side sheet;

Fig. 7 is a similar detail view illustrating an alternative form which is applicable to either the center or side brick;

35 Fig. 8 is a view similar to Fig. 5 showing a center brick having one edge thereof provided with spaced surfaces for contact with the water tube, and

Fig. 9 is an enlarged detail view of the side 40 or wing brick shown in Fig. 2.

In Fig. 1 of the drawings, for purposes of illustration I have generally indicated a locomotive firebox 1 having side sheets 2, a flue sheet 3 and a rear sheet 4. This firebox 45 is provided in the usual manner with a plurality of water circulating tubes extending longitudinally thereof in substantially parallel relation to each other. In practice, these tubes are usually vertically inclined and extend from the lower part of the flue sheet 3 50 to the upper part of the rear sheet 4 to aid the rapid circulation of the water in its conversion into steam. The tubes designated 5 are usually referred to as the side tubes, while 55 the tubes 6 are the intermediate or center tubes.

As herein shown the refractory arch extends from the flue sheet 3 rearwardly to a point in suitably spaced relation from the rear sheet 4 and is supported upon and between the tubes 5 and 6 and the side sheets 2 of the firebox. This arch is composed of a plurality of individual refractory bricks or units, of which two forms are used. Thus 60 65 the center or intermediate arch brick 7 which

rest upon and are supported by the tubes 5 and 6 may be provided on opposite edges with arcuately curved seating surfaces 8 for engagement upon the water circulating tubes, or these opposite edges of the baffle brick may each be provided with the two convex surface portions 9 providing for spaced points of contact upon the water tubes. This form is particularly advantageous when used as a side brick supported on trunnions and the outer tubes in those instances where the distance between the outer side tubes 5 and the side sheets 2 of the firebox varies from one end to the other of the arch. It will also be understood that such spaced contact surfaces 9 may also be provided upon one edge of the side brick of the arch which are indicated at 10.

The side brick 10 as shown in Figs. 2 and 9 of the drawings, are provided along one edge with the concave seating surface 11 to engage on the tube 5, while the opposite edge of the brick is curved reversely to the intermediate portion thereof to be presently described in detail as indicated at 12, thereby providing a convex bearing surface 13 for contact against the side sheet 2 and permitting these side brick to automatically accommodate themselves to variations in the space between the side tubes 5 and the firebox side sheets 2. In some instances, it is desirable to have all of the brick constituting the arch wall positioned in a common horizontal plane, and in such cases, instead of providing the side brick with the curved edge portions 12, I may provide the underside of each of these brick at one edge thereof with either a flat or slightly concaved seat indicated at 14 to rest upon the lug or trunnion indicated at 15 which is welded or otherwise permanently fixed to the side sheet 2.

I may also provide the center brick of the arch at their opposite edges with the lower convex surfaces 16 merging into the intermediate concave lower surface of the brick to rest upon the surfaces of the spaced water tubes. Such convex surfaces on the edges of the brick as shown in either Figs. 7 or 8 are of advantage when the size of the arch tubes vary or when they may be somewhat out of alignment.

Referring now to Fig. 5 of the drawings, it will be understood that the following description applies equally well to both the center and the side brick, and it will be noted that the lower surface 17 of the brick extends in a continuous concave arc between the opposite edge surfaces which seat or rest upon the spaced supporting elements of the firebox structure. Assuming that this arcuate lower surface of the brick has a center at A, the upper surface 18 of the brick extends in a parallel arc from the same center and for the major part of the distance between the center line of the brick and the opposite edges thereof. Therefore, that part of the 120 125 130

brick between the lines B radiating from the center A has a structure of uniform thickness so that all of this major portion of the brick will offer equal resistance to the effects of high combustion chamber temperatures and to the abrasive action of coal and ash particles.

The remainder of the upper surface of the brick from the ends of the intermediate section 18 thereof to the opposite edges of the brick which are seated upon the supporting elements describe different convex arcs as indicated at 19 from the shorter radii C at either side of the center line of the brick. These edge sections 19 of the upper surface of the brick are curved on lines which are tangent to the intermediate section 18 of said surface and merge into the latter. As will be apparent, these edge portions 19 of the upper surface of the brick extend from the intermediate section 18 of said surface in non-parallel convergent relation with the extended arc of the lower surface 17 of the brick. Thus from the lines B, the edge portions of the brick adjacent to the supporting elements of the firebox structure gradually decrease in thickness relative to the major intermediate part of the brick structure.

With reference to the side brick of the arch shown in Figs. 2 and 9 of the drawings, it will be understood that the upper surface of the edge portion 12 of the brick extends from the intermediate upper surface section 18 in a reverse arc, or is concave instead of convex, said concave arcuate surface having its center at a point above a line connecting the center of the water tube with the point of engagement of the convex edge face 13 of the brick with the side sheet 2 of the firebox.

From the foregoing description considered in connection with the accompanying drawings, it is believed that the several novel features of my new arch brick construction as well as the advantages thereof in practical use will be readily understood. By reason of such improvements, I have succeeded in materially increasing the period of serviceability of such arch brick before replacement is required. At the same time, it is evident that such improvements readily lend themselves to quantity production of the arch brick on a large scale without appreciable increase in manufacturing cost.

While I have herein shown and described several simple and practical forms of my present improvements, it is nevertheless to be understood that the essential features thereof are also capable of embodiment in various other alternative structures, and I accordingly reserve the privilege of resorting to all such detail changes therein as may be fairly embodied within the spirit and scope of the invention as claimed.

I claim:

1. A refractory arch brick having opposite

edge portions provided with means for engagement upon spaced supporting elements of a firebox structure, said brick being arched between said edge portions and having an upper convex surface extending between said edge portions in substantially concentric relation with the lower concave surface of the brick to provide central and intermediate sections of the brick structure of substantially uniform thickness, and the upper surfaces of said edge portions of the brick being curved on relatively short arcs merging into the remaining upper surface of the brick and in convergent relation to the lower concave surface of the brick to thereby provide continuations of the brick arch constituting edge portions on the brick of gradually decreasing thickness for contact with the spaced supporting elements.

2. A refractory arch brick for firebox baffle walls adapted to be supported upon and between spaced elements of the firebox structure, said arch brick having an edge portion formed to provide a plurality of inwardly converging convex surfaces for contact with one of the supporting elements which extend continuously throughout one dimension of the brick.

3. A refractory arch brick for firebox baffle walls adapted to be supported upon and between spaced elements of the firebox structure, said arch brick having an edge portion provided with a plurality of convex surfaces of unbroken continuity throughout one dimension of the brick, one or all of which are adapted to contact upon one of the supporting elements.

In testimony that I claim the foregoing as my invention, I have signed by name hereto.
